(57) **CLAIM**

The ornamental design for a differential pressure transmitter as shown and described.

DESCRIPTION

The patent or application file contains at least one drawing executed in color. Copies of this patent or patent application

publication with color drawing(s) will be provided by the Office upon request and payment of the necessary fee.

1. Differential pressure transmitter

2. Differential pressure transmitter

3. Differential pressure transmitter

4. Differential pressure transmitter

4.7 : Back

Differential pressure transmitter with two independent measuring systems for monitoring the differential pressure of air, gases, vapors and liquids with an integrated display below a translucent lid (design 3 and 4).

The broken line showing of non-claimed subject matter is included for the purpose of illustrating environmental features and forms no part of the claimed design.
